UNITED STATES PATENT OFFICE.

WARREN S. BELDING, OF ENGLEWOOD, ASSIGNOR TO THE BELDING MOTOR AND MANUFACTURING COMPANY, OF CHICAGO, ILLINOIS.

ARMATURE-PLATE.

SPECIFICATION forming part of Letters Patent No. 415,695, dated November 26, 1889.

Application filed July 7, 1888. Serial No. 279,313. (No model.)

To all whom it may concern:

Be it known that I, WARREN S. BELDING, a citizen of the United States, residing at Englewood, in the county of Cook and State of Illinois, have invented certain new and useful Improvements in Plates for Armatures; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates more particularly to plates to be used in the construction of segmental sections of armatures, which sections are to be built up and wound and united to form the complete ring on cylinder after winding. It has been found desirable to construct the armature-ring in segments in order that the winding may be more easily accomplished and that a coil which has been rendered defective by use may be more easily removed and replaced.

In the accompanying drawings, Figure 1 is a view of two of my improved plates disconnected. Fig. 2 is an end view of a completed ring formed of the plates. Fig. 3 shows a modification of the form of plate shown in the preceding figures. Fig. 4 shows the side of a completed ring without the coils.

Referring to Figs. 1 and 2, A A are plates of such dimensions and form as that they will fit together end to end and constitute a complete circle. The meeting ends are so formed as to interlock and form a joint, by which the plates are held to each other. Each plate in Fig. 1 has a projection A' at its ends, extending inwardly or outwardly in a line passing through the center of the circle of which the plate forms a part. I prefer to form each such projection with parallel sides, so that its outer portion is of the same width as its inner portion, but it may be of other shape; and I prefer to form one of the said projections to extend toward and the other from the center of the circle. The special advantage of this latter feature will be stated below. Between each such projection and the body of the plate is a notch A² of sufficient

width to receive the projection A' on the end of the plate A, which is brought into juxtaposition to it. Said notches are best made with parallel sides; but they may be of other shape, so long as they are as wide at their outer portion as the widest portion of said projections, in order that said notches may receive said projections when the said sections are moved toward or upon each other on a line passing through the ends of both sections. The plates A may or may not have polar extensions A³. By making each plate for the complete ring a half or other aliquot part of the circle all the plates may be identical and cut from the sheet of metal in the same die.

In building the half of the armature the plates are placed side by side to make the desired thickness. Sheets of insulation material cut in the die in which the plates are cut may be placed between the plates, and the plates may be held together temporarily by any suitable means. The similar ends of the plates and the insulated sheets are laid upon each other and the ends are made even with each other, none being extended beyond the rest to make spaces between the ends. When thus massed and temporarily held together, the bobbin-spaces B of the section are wound with wire to form the coils C. When the coils have been thus wound, they hold the plates of the section together. The two halves may now be easily united by sliding one sideways upon the other, so that the projections A' on one half enter the notches A² on the other half; or the two halves may be slid endwise upon each other, the projection A' sliding in the channels formed by the notches A². The ring or cylinder is now ready to be mounted upon a shaft by means of a spider. Holes D between the bobbin-spaces in the plates form continuous holes between the coils through the sections for the reception of bolts used to bind the spider or spiders to the armature.

In Fig. 3 the ends of the plates lock by dovetailing, a projection E being formed on one end and a corresponding notch being formed on the other. The halves of the armature built of these plates must be moved upon each other in the direction of the axis, while

those built of the plates shown in Fig. 1 may be moved upon each other in the direction of the axis and also in a direction transverse to the axis. The latter mode is preferable, because the sections are not so apt to bind upon each other before each is in place. In the form shown in Fig. 1 each projection A' merely enters the notch in the end of the plate which is to stand opposite to it in the complete armature, while in the other form the projections E must move parallel to the axis of the armature through the channel formed by the notches E', and, as the dovetailing must fit closely, care must be exercised to get the ends of the plates so even as to allow the sections to move readily upon each other. It is to be observed that in neither form do a portion of the plates extend beyond the others, so as to leave spaces for the projecting ends of the plates of the opposite section to enter. This I consider an important improvement.

I have found in practice that it is difficult to interlock the sections by means of the projecting ends. The ends of some of the plates are apt to turn sidewise sufficiently to prevent the meeting ends of the sections from intermeshing readily, and if insulation-sheets are used between the metal plates the ends of said sheets are apt to be met and pushed inwardly by the ends of the metal plates of the opposite section. In consequence of this the insulation-sheets must be made thick. By the use of my improved plates no such trouble is met with in using either the metal plates or the insulation-sheets, and the insulation-sheets may be cut of thin sheets, whereby the thickness and cost of the armature are reduced.

I claim as my invention—

40 1. A sheet-metal armature-plate forming a portion of a circle and having its ends provided with projections and with notches as wide at their inner portions as the widest portion of said projections, and formed to interlock with the ends of a similar plate, substantially as and for the purpose set forth.

2. A sheet-metal armature-plate forming a portion of a circle and having its ends provided with projections and notches having parallel sides and formed to interlock with the ends of a similar plate, substantially as and for the purpose set forth.

3. A sheet-metal armature-plate forming a portion of a circle and having its ends provided with projections and with notches as wide at their outer ends as the widest portion of said projections, both said projections and notches extending in a line passing through the center of a circle of which the plate forms a part, substantially as and for the purpose set forth.

4. A sheet-metal armature-plate forming a portion of a circle and having its ends provided with projections and notches, each having parallel sides and extending in a line passing through the center of the circle of

which the plate forms a part, substantially as and for the purpose set forth.

5. A sheet-metal armature-plate forming a portion of a circle and having its ends provided with projections and with notches as wide at their outer portions as the widest portion of said projections, one of each of said projections and notches extending from and the other of each of said notches and projections extending toward the center of the circle of which said plate forms a part, substantially as shown and described. 75

6. A sheet-metal armature-plate forming a portion of a circle and having its ends provided with one or more projections and notches, each having parallel sides, one of each of said projections and notches extending from and the other of each of said notches and projections extending toward the center of the circle of which said plate forms a part, substantially as shown and described. 80

7. A sheet-metal armature-plate forming a portion of a circle and having polar extensions and having its ends provided with projections and with notches as wide at their outer portions as the widest portion of said projections, one of each of said projections and notches extending from and the other of each of said notches and projections extending toward the center of the circle of which said plate forms a part, substantially as shown and described. 95

8. A sheet-metal armature-plate forming a portion of a circle and having polar extensions between the bobbin-spaces and having its ends provided with one or more projections and notches, each having parallel sides, one of each of said notches and projections extending from and the other of each of said projections and notches extending toward the center of the circle of which said plate forms a part, substantially as shown and described. 100

9. A sheet-metal armature-plate forming a portion of a circle and having polar extensions A³, and holes D between the bobbin-spaces, and having its ends provided with one or more projections and notches, each having parallel sides, one of each of said projections and notches extending from and the other of each of said notches and projections extending toward the center of the circle of which said plate forms a part, substantially as shown and described. 110

10. A sheet-metal armature-plate forming a portion of a circle and having its ends provided with projections and notches formed to interlock with the ends of a similar plate, and having holes D between the bobbin-spaces to form continuous holes through the sections for the reception of spider-bolts, substantially as described. 120

11. A sheet-metal armature-plate forming a portion of a circle and having its ends provided with projections and notches formed to interlock with the ends of a similar plate, and having the bobbin-spaces B, and the 130

holes D and polar extensions A³ between said bobbin-spaces, substantially as shown and described.

12. A sheet-metal armature-plate forming a part of a circle and having its ends provided with projections A' and notches A², extending in a line passing through the center of the circle of which the plate forms a part, and having the bobbin-spaces B and polar extensions A³ between said bobbin-spaces, substantially as herein described.

13. A sheet-metal armature-plate forming a part of a circle and having its ends pro-

vided with projections A' and notches A², extending in a line passing through the center of the circle of which the plate forms a part, and having the bobbin-spaces B and polar extensions A³ and holes D between said bobbin-spaces.

In testimony whereof I affix my signature in presence of two witnesses.
